[57] ABSTRACT

Apparatus adapted for movement underwater to partially surround and cut underwater anchoring means such as steel ropes, hawsers, chains, cables and the like including a housing carrying an explosive cutting charge and having an arm pivotally mounted in the housing and extending therefrom. The arm is biased for movement to an open position and carries charge igniting means responsive to contact by the anchoring means to be cut in the open position of the arm for detonating the charge and severing the anchoring means. The charge igniting means is provided with several safety devices including a shear pin which is ruptured by contact with the anchoring means and a piston chamber which must be filled with water to enable detonation of the charge, thereby requiring the apparatus to be submerged. The arm may also be restrained from assuming the open position by a wire connecting the arm and the housing which is broken by contact with the anchoring means to be cut. The apparatus is adapted to be disposed of after a single use.

**DEVICE FOR CUTTING STEEL ROPES, HAWSERS,
CHAINS, CABLES AND THE LIKE UNDER THE
WATER SURFACE**

This invention relates to a device for cutting steel ropes, hawsers, chains, cables and the like under the surface of the water, comprising a capture and cutting device arranged for movement towards the object to be cut to partially surround it, so that the cutting means is actuated by the object to be cut.

In maritime and river navigation, cutting devices have been used by mine-sweeping detachments for cutting anchoring devices such as steel ropes, hawsers and chains to which sea-mines, steel nets or like devices are attached. Generally, several of these cutting devices are drawn through the water on a tow rope at a spaced distance apart. When a cutting device with its capture arms arranged at an angle to each other comes into the vicinity of a steel rope, the rope is guided along the capture arms into a chamber having a widened portion behind the intersection of the arms in which a chisel-like tool is countersunk. The tool is held taut by a spring or is actuated by a propelling charge such that when the steel rope penetrates the chamber, a projecting pin is depressed for actuating the spring or a cocked firing pin such that the releasing of the spring or the ignition of the propelling charge causes the chisel to be rapidly forced against the steel rope.

The prior art cutting devices operating in the above-described manner have generally proven successful in all instances in which a specified cross section is not exceeded by the steel ropes or chains to be cut. However, these cutting tools driven by conventional means are very large and heavy so that to achieve an increase in efficiency, an even heavier embodiment would have to be used. In addition, cutting devices of this type are equipped throughout with their own buoyancy members. When the ropes, hawsers or chains are not cut during their first passage through the cutting device, then the cutting device is applied again. However, if the second pass does not result in complete cutting, then a grappling rope is generally paid out from the mine sweeper and is utilized for tearing the steel rope or chain from its anchorage. Due to the buoyancy of sea-mines, the latter can then be disarmed at the water surface.

The present invention overcomes the aforementioned disadvantages by providing a cutting device for underwater steel ropes, hawsers, chains, cables and the like having an improved cutting efficiency and a simple construction. The cutting device is preferably formed of such materials that the cutting device is economically disposable after a single use and is not dependant upon additional buoyancy elements for floating through the water.

According to the present invention, there is provided a device for cutting steel ropes, hawsers, chains, cables and the like under the surface of water including a capture and cutting device arranged for movement towards the object to be cut to partially surround it with the cutting means being actuated by the object to be cut. The capture and cutting device is provided with a cutting charge carrier, an arm pivotable to an open position, and means for restraining the arm against assuming the open position such that when the device is in the open position, it cooperates with the object to be cut to cause the ignition of the cutting charge.

In accordance with an advantageous feature of the present invention, the pivotable arm is constructed as an angle lever having a control plate such that in an open position, the arm can be operated by the object to be cut so that a laterally projecting retaining ring on the control plate brings about the release of a spring-loaded piston. The working stroke of the piston is transmitted via a water column in the piston chamber to a push-rod which moves a rocker arm mounted on a pivotable arm and carrying an ignition pin for igniting a firing detonator associated with the cutting charge.

In accordance with another feature of the present invention, the arm which is mounted in a recess of the cutting charge carrier is provided with a spring located about spring axis for biasing the arm into an open position. A retaining wire which is adapted to be destroyed by the object to be cut connects the cutting charge carrier and the arm and maintains the arm in the closed position against the opening pressure of the spring. Also, the ignition of the cutting charge by the firing pin is only possible according to the invention after removing a safety device.

The present invention provides several safety devices for the cutting apparatus including a shear pin connecting the control plate to the pivotable arm which must be ruptured before the firing pin can ignite the cutting charge. In addition, the operation of the ignition device is only possible under water in that the actuating means for the firing pin includes a water column with an entry slot and a small lateral outlet bore interposed between mechanical actuating means for the firing pin.

In accordance with still another feature of the present invention, the cutting charge carrier is provided with a stabilizer and a ceramic plate is located between the cutting charge and tow rope to protect the tow rope from damage by detonation of the charge. In addition, both the housing of the cutting charge carrier and the arm are constructed essentially of plastic material to provide an extremely lightweight cutting device capable of floating without additional buoyancy members.

It is therefore an object of the present invention to provide a device for cutting underwater anchoring devices which overcomes the disadvantages of the prior art.

It is another object of the present invention to provide an inexpensive cutting device which is disposable after a single use.

It is still another object of the present invention to provide a lightweight cutting device which maintains buoyancy in the water without the aid of addition buoyant members.

It is a further object of the present invention to provide an underwater cutting device requiring submersion for operation.

These and other objects, features and advantages of the present invention will become more obvious from the following description when taken in connection with the accompanying drawings, wherein:

FIG. 1 is a perspective view of a capture and cutting device in accordance with the present invention;

FIG. 2 is a longitudinal section through the cutting device of FIG. 1 with the pivotable arm in closed position;

FIG. 3 is a cutaway view of FIG. 2 with the pivotable arm in the open position and a firing pin readied for igniting the charge.

FIG. 4 is the same cutaway view as in FIG. 3 showing a firing detonator pierced by the firing pin.

Referring now to the drawings wherein like reference numerals are used throughout the various views to designate like parts and more particularly to FIG. 1, there is shown a cutting charge carrier housing 1 preferably formed of a plastic material and receiving a cutting charge 2 having a hollow charge effect, a connecting means 4 for a tow rope 5 located at the transition point of the housing and a stabilizer 3. As shown in FIG. 2, 10 a ceramic plate 6 is embedded in the housing between the tow rope 5 and the cutting charge 2 which is provided with a conventional metal lining to improve the charge cutting efficiency. A firing detonator 7 is in contact with the cutting charge 2 and serves initially for firing the charge.

The housing 1 is provided with an aperture 8 adjacent to the cutting charge 2 and extending to the upper edge of the housing 1 and a pivotable arm 9 preferably formed of a plastic material and having a configuration of an angle lever is arranged within the aperture for pivoting about a pivot 24. A spring 11 wound around a spring shaft 10 biases the arm 9 into the open position. However, a retaining wire 12 connects the cutting charge carrier housing 1 and the arm 9 for preventing the arm from assuming the open position. The retaining wire 12 is adapted to be destroyed by the object 27 to be cut, or the wire may be removed by hand. In the closed position, i.e., in the unaffected condition of the wire 12, the cutting charge carrier 1 and the arm 9 are both provided with guiding surface configurations which aid the capture of the object to be cut.

As shown in FIG. 2, when the arm 9 is in the closed position, the short end of the angle lever forming the arm is disposed in the aperture 8 and a control plate 13 secured in the arm by a shear pin 9a is disposed deep in the cavity of the cutting charge 2. The control plate includes a projecting retaining ring 15 and the plate is pivoted on the arm 9 by a pivot 14. The shear pin serves as a safety device for preventing improper charge detonation by preventing pivoting of the control plate until sufficient pressure is exerted on the control plate to rupture the pin.

A collar 16 of a piston 17 is biased into abutment against the retaining ring 15 by a compression spring 18 which actuates the piston with the portion of the piston above the collar 16 being guided in a piston chamber 19. Above the piston 17, the piston chamber is provided with a lateral slot 20 as an inlet and a small lateral bore 21 as an outlet. In the continuation of the piston chamber 19, a push-rod 22 is movably mounted in the arm 9 for striking the side edge of a rocker arm 23 mounted on the pivot 24. A leaf spring 26 supported on the rocker arm 23 and the inner wall of the arm 9 constantly biases the rocker arm 23 against the push rod 22 and an ignition pin 25 projects downwardly from the opposite end of the rocker arm 23.

In operation as an underwater cutting device, a plurality of the cutting devices are connected to the tow rope of a mine sweeper at a predetermined spacing. The free end of the tow rope 5 is provided with a float having fins which permits the tow rope 5 to be held in a wide arc out of the wash of the ship, thus enabling the tow rope to cover an area as wide as possible. In accordance with the present invention, the formation of the housing and arm from plastic material provides extraordinarily light cutting devices with flat stabilizers 3

which require no additional buoyancy members. As the cutting device submerges, the water penetrates the piston chamber 19 through the slot 20 and forms a water column 28 to complete the firing pin actuating mechanism. A small amount of water leaves the piston chamber 19 through the small lateral bore 21. However, the chamber is constantly refilled through the slot 20.

As the cutting device is carried through the water, an object 27 to be cut, e.g., a steel rope, arrives in front of the retaining wire 12 breaking the wire so that the force of the spring 11 causes the entire arm 9 to be brought into the open position as shown in FIG. 3. It is, of course, also possible to remove the retaining wire 12 by hand, before inserting the cutting device in the water, so that the arm 9 is in the open position. This solution has the advantage that the open capture device covers a greater area and has a greater chance of catching a steel rope than a closed device. In the open position, the point of the ignition pin 25 is located immediately in front of the firing detonator 7 of the cutting charge 2. As the steel rope 27 is surrounded by the capture device, the rope presses against the control plate 13 causing the safety shear pin 9a to rupture. This results in the retaining ring 15 being displaced in such a way that the collar 16 of the piston 17 is released and forced forward by the compression spring 18 to strike the water column 28. The pressure of the water column 28 operates on the push-rod 22 forcing the push-rod from its seat to actuate the rocker arm 23 against the force of the leaf spring 26 and causing the rocker arm to pivot about pivot 24 so that the point of the ignition pin 25 punctures the firing detonator 7. The firing detonator ignites the cutting charge 2 and since the steel rope 27 to be cut is exactly in front of the cutting charge 2, it is broken cleanly by the cutting blast of the detonating cutting charge.

The cutting charge, upon ignition by the detonator 7 deforms the metallic lining into a cutting edge, which 40 cuts through the steel rope or an anchoring hawser, a chain or even a cable at high speed. However, it is desired that the tow rope 5 should not be unduly damaged by the charge. For this purpose, the ceramic plate 6 is arranged as a protective screen between the cutting charge 2 and the tow rope 5 to prevent damage of the tow rope. After combed an area of sea-mines, the burnt-out cutting devices are removed from the tow rope, thrown away and replaced by new ones, so that during the next passage the adjacent area can be combed.

Obviously, many modifications and variations of the present invention are possible in the light of the above teachings. It should therefore be understood that within the scope of the appended claims, the invention may be practiced otherwise than as specifically described.

We claim:

1. Apparatus adapted for movement underwater to partially surround and cut an underwater anchoring means such as a steel rope or chain comprising a housing, cutting charge carried by said housing, arm means connected to said housing and mounted for pivotal movement into an open position with respect to said housing, said arm means in the open position being responsive to the anchoring means for igniting said cutting charge to sever the anchoring means, and means for restraining the movement of said arm means into the open position.

2. Apparatus as defined in claim 1 wherein said arm means includes means carried thereby and arranged for contacting the anchoring means in the open position of said arm means and responsive thereto for igniting said cutting charge.

3. Apparatus as defined in claim 1 wherein said restraining means is a wire connecting said housing and said arm means, said wire adapted to be broken by contact with the anchoring means thereby permitting said arm means to assume the open position.

4. Apparatus as defined in claim 1 wherein said housing is provided with an aperture, said arm means being pivotably mounted in said aperture, and a spring is arranged in said aperture for biasing said arm means into the open position.

5. Apparatus as defined in claim 4 wherein said arm means is formed as an angle lever and includes means carried thereby and arranged for contacting the anchoring means in the open position of said arm means and responsive thereto for igniting said cutting charge.

6. Apparatus as defined in claim 5 wherein said igniting means includes a control plate mounted for pivotal movement in response to contact by the anchoring means, a rocker arm mounted for pivotal movement and carrying an igniting pin for contacting said cutting charge to ignite said charge, and actuating means responsive to the pivotal movement of said control plate for causing movement of said rocker arm and said igniting pin whereby said igniting pin ignites said cutting charge.

7. Apparatus as defined in claim 6 wherein said actuating means includes a piston chamber adapted to be filled with water, a spring biased piston arranged for movement in said chamber in response to the movement of said control plate, and a push-rod responsive to the movement of said piston via the water in said chamber for pivoting said rocker arm to cause ignition of said charge by said igniting pin.

8. Apparatus as defined in claim 7 wherein said control plate includes a retaining ring extending therefrom in abutment with a portion of said piston to prevent movement of piston in response to the spring force whereby movement of said control plate causes the retaining ring to move out of abutment with said piston to permit movement of said piston in response to the spring force.

9. Apparatus as defined in claim 8 wherein said control plate is provided with means fixedly connecting said control plate to said arm means, said means being ruptured in response to said control plate contacting the anchoring means to permit pivotal movement of said control plate.

10. Apparatus as defined in claim 9 wherein said connecting means is a shear pin.

11. Apparatus as defined in claim 7 wherein said piston chamber is provided with a lateral inlet slot and a small lateral outlet bore for permitting water to enter and fill said chamber when said apparatus is submerged.

12. Apparatus as defined in claim 8 wherein said cutting charge is provided with a firing detonator and said igniting pin contacts said firing detonator for igniting said cutting charge.

13. Apparatus as defined in claim 1 wherein said housing is provided with a stabilizer.

14. Apparatus as defined in claim 1 wherein said housing includes means for connecting a tow-rope for

towing said apparatus through the water and a ceramic plate is disposed in said housing between said cutting charge and said tow rope connecting means for shielding the tow rope from the charge detonation.

5 15. Apparatus as defined in claim 14, wherein said charge is provided with a metal lining and said ceramic plate is arranged substantially parallel to said charge and said tow rope connecting means.

10 16. Apparatus as defined in claim 1 wherein said housing and said arm means are formed of plastic material.

17. Apparatus as defined in claim 8 wherein said push-rod is arranged at one end of said piston chamber adapted for contact with the water in said chamber and

15 a spring is provided in said arm means for biasing said rocker arm into contact with said push-rod whereby the force of the movement of said piston is transmitted to said push rod via the water in said chamber causing the push-rod to pivot said rocker arm against the bias of said spring.

20 18. Apparatus as defined in claim 17 wherein said housing is provided with a recess in which said cutting charge is carried, said control plate being positioned along said arm means proximate to said recess.

25 19. Apparatus as defined in claim 18 wherein said control plate is received in said recess in the closed position of said arm means.

20 20. Apparatus as defined in claim 8 wherein a wire connects said housing and said arm means for restraining the movement of said arm means into the open position, said wire adapted to be broken by contact with the anchoring means thereby permitting said arm means to assume the open position.

25 21. Apparatus as defined in claim 20 wherein said housing is provided with a stabilizer portion extending therefrom and a ceramic plate is disposed in said housing between said cutting charge and said stabilizer portion.

20 22. Apparatus as defined in claim 21 wherein said arm means and said housing is formed of plastic material.

25 23. Apparatus as defined in claim 2 wherein said igniting means includes a control plate mounted for pivotal movement in response to contact by the anchoring means, a rocker arm mounted for pivotal movement and carrying an igniting pin for contacting said cutting charge to ignite said charge, and actuating means responsive to the pivotal movement of said control plate for causing movement of said rocker arm and said igniting pin whereby said igniting pin ignites said cutting charge.

30 24. Apparatus as defined in claim 23 wherein said actuating means includes a piston chamber adapted to be filled with water, a spring biased piston arranged for movement in said chamber in response to the movement of said control plate, and a push-rod responsive to the movement of said piston via the water in said chamber for pivoting said rocker arm to cause ignition of said charge by said igniting pin.

35 25. Apparatus as defined in claim 3 wherein said arm means includes means carried thereby and arranged for contacting the anchoring means in the open position of said arm means and responsive thereto for igniting said cutting charge.

40 26. Apparatus as defined in claim 25 wherein said igniting means includes a control plate mounted for pivotal movement in response to contact by the anchoring

means, a rocker arm mounted for pivotal movement and carrying an igniting pin for contacting said cutting charge to ignite said charge, and actuating means responsive to the pivotal movement of said control plate for causing movement of said rocker arm and said igniting pin whereby said igniting pin ignites said cutting charge.

27. Apparatus as defined in claim 26 wherein said actuating means includes a piston chamber adapted to be filled with water, a spring biased piston arranged for movement in said chamber in response to the movement of said control plate, and a push-rod responsive to the movement of said piston via the water in said chamber for pivoting said rocker arm to cause ignition of said charge by said igniting pin.

28. Apparatus as defined in claim 16 wherein said arm means includes means carried thereby and arranged for contacting the anchoring means in the open position of said arm means and responsive thereto for igniting said cutting charge.

29. Apparatus as defined in claim 28 wherein said igniting means includes a control plate mounted for pivotal movement in response to contact by the anchoring means, a rocker arm mounted for pivotal movement and carrying an igniting pin for contacting said cutting charge to ignite said charge, and actuating means responsive to the pivotal movement of said control plate for causing movement of said rocker arm and said igniting pin whereby said igniting pin ignites said cutting charge.

30. Apparatus as defined in claim 29 wherein said actuating means includes a piston chamber adapted to be filled with water, a spring biased piston arranged for movement in said chamber in response to the movement of said control plate, and a push-rod responsive to the movement of said piston via the water in said chamber for pivoting said rocker arm to cause ignition of said charge by said igniting pin.
